WILLIAM H. GREENFIELD, OF PHILADELPHIA, PENNSYLVANIA.

RAIL-HEATING DEVICE

Application filed May 12, 1927. Serial No. 190,982.

My invention relates to rail heating devices and more particularly to electric heaters designed to prevent the accumulation of ice and snow around rail switches and 5 derail points without interference with their operation. Primarily the invention consists of heat radiating units positioned at switch or derail points or at intervals along a railway track, the units being electrically operated from local or distant stations.

To fully explain the object of my invention I shall refer briefly to the operation of well-known types of rail heaters. Heretofore, it has been common in this art to 10 heat rails by resistance conductors extending along the sides of the rails or beneath them, the conductors being insulated from the rails by material which is a non-conductor of electricity but a conductor of heat. 15 The use of such devices has not proved to be altogether satisfactory by reason of the operative inefficiency due to losses in heat transmission and on account of the excessive cost of installation. Still other devices have 20 not been able to withstand the vibration or the severe weather conditions to which railway tracks are subjected.

To obviate the foregoing difficulties, my invention provides a means of heating rails 25 by direct radiation from a high resistance heating element which is adapted to raise the temperature of the rail to which it is attached to a sufficiently high degree to prevent the formation of ice or snow in the neighborhood of the rail. My invention also 30 provides a means of reducing losses in heat transmission to a minimum.

Supplementing the advantages already described are those derived from the use of a 35 heating device which though durable and waterproof is nevertheless simple in structure and inexpensive to manufacture.

Other features and advantages of my invention will be apparent from the detailed 40 description which follows, the description having reference to the accompanying drawings which represent a typical embodiment of the invention, and in which:

Fig. I is a perspective view of the heating 45 element and the casing in which it is retained.

Fig. II is a perspective view of a portion 50 of a rail, illustrating one form of my invention in place.

Fig. III is a cross sectional view of a rail

with the heater attached taken as indicated by the arrows III—III in Fig. IV.

Fig. IV is a cross sectional view of the same taken as indicated by the arrows 60 IV—IV in Fig. III, and

Fig. V is an enlarged sectional view of one end of the casing illustrating the method by which the heating element is secured to the casing and insulated therefrom.

In the drawings there is shown a portion 65 of an ordinary track switch comprising a main rail R with a heating unit of convenient size attached to the hollow of the rail and enclosed in a protective casing comprehensively designated by the numeral 6. To 70 secure the casing 6 to the rail R the end pieces 8 are provided with ears 9 which may be bolted or otherwise firmly held against the central web of the rail. Apertures 13 in the end pieces 8 admit passage of the electrical conductor 12 through the casing to the heating element 5. In electric connection with the conductor 12 the heating element 5 occupies the trough of the fillet junction between the central web and base flange 75 of the rail R, but contacts only with the sockets 14 in which it is supported. The casing 6 is preferably lined with asbestos 80 or other heat insulating material in order to retain the heat radiating from the element 5 within the enclosure bounded by the casing and the hollow of the rail. The lining 7 also affords a reflecting surface to direct the radiation from the heating element 5 towards the rail R.

Referring particularly to Fig. V, I have 85 illustrated one form of bushing for supporting the heating element 5 within the casing 6. It comprises a porcelain insulator 11, fitting in the rounded flange 10 of the casing 6 through which the conductor 12 is free 90 to pass, together with a terminal socket 14 to which the bared wire is sealed. The socket 14 is adapted to receive the end of the heating element 5 in its hollowed recess in 100 the annular space surrounding the insulator 11. A helical spring 15 is provided to enable movement of the insulator 13 so that the heating element 5 may be removed with ease. The interior of the insulator 11 is shown 105 filled with plaster 16 for securing the conductor 12 in a firm connection with its terminal 14. Between the insulator 10 and the terminal socket 14 a washer 17 is interposed.

The heating element 5 may consist of an 110

elongated rigid non-metallic resistor bar of convenient size and offering high resistance to the passage of current. For this purpose, I preferably employ what is commercially known as a "glow bar", being a carborundum element especially suitable as a resistor bar. Likewise I may employ a heating element known as "nichrome" or any of the materials commonly used as resistance conductors. By virtue of its close proximity to the web and bottom flange of the rail R, the resistor bar 5 is capable of transmitting intense heat to the exposed surfaces of the rail. As the enclosure bounded by the hollow of the rail R and the heat insulated casing 6 is entirely devoid of heat conducting elements with the exception of the rail itself the air in the enclosure serves as the sole medium of heat transmission between the element 5 and the rail. Thus, heat losses by conduction are reduced to a minimum. Furthermore, the base flange of the rail is directly exposed to heat radiation, this being the portion of the rail which it is most desirable to heat to effect a thorough melting of ice or snow around switch points.

In the arrangement shown, the heating unit is waterproof and well protected from injury. By slight modification in the shape of the casing the heater may be adapted for use on rails at points where fish plates or through bolts are located without departing from the scope of the present invention.

It will be apparent that the device may also be adapted for use on third rails or current carrying rails, the heating circuit being insulated and independent of the rail to which it is attached. By reason of the portable character of the units they may be installed either for permanent or temporary use. When permanently installed the resistance bars 5 may be easily replaced or removed by virtue of the peculiar construction of the spring actuated sockets in which they are held.

Having thus described my invention, I claim:

1. A rail heating device comprising a bare electric heating element, and means to support said element in spaced relation from the rail with air serving as the sole medium of heat transmission therebetween.

2. A rail heating device comprising a bare electric heating element in the form of an elongated resistor bar, and means engaging the bar at opposite ends to support it in longitudinally spaced relation from the rail with air serving as the sole medium of heat transmission therebetween.

3. A rail heating device comprising a bare electric heating element in the form of a rigid elongated resistor bar, and yielding means releasably engaging the bar at opposite ends to support it in longitudinally spaced relation from the rail with air serving as the

sole medium of heat transmission between the resistance bar and the rail aforesaid.

4. A rail heating device comprising a bare electric heating element, means to support said element in spaced relation from the hollow of the rail with air serving as the sole insulation therebetween, and a protective casing affording a reflecting surface to direct radiation from the heating element toward the rail.

5. A rail heating device comprising an electrical resistor bar, means to support the bar longitudinally within the trough of the fillet juncture between the web and base flange of the rail with air serving as the sole insulation therebetween, and a protective casing affording a reflecting surface to direct radiation from the bar inwardly toward the rail as well as downwardly toward the base flange.

6. A rail heating device comprising a bare electric heating element in the form of a rigid elongated resistor bar, and spring urged sockets releasably engaging the bar at opposite ends to support it in longitudinally spaced relation from the hollow of the rail with air serving as the sole insulation between the bar and the rail aforesaid.

7. A rail heating device comprising a casing secured to the rail and extending therewith, and an electrical heating element in the form of a rigid resistor bar centrally located in the space between said casing and rail whereby the web and base flange of the rail are exposed to direct radiation from the heating element.

8. A rail heating device comprising a casing having end pieces secured to the rail, said casing forming with the hollow of the rail an enclosure of substantially triangular cross section, and an electrical heating element in the form of a rigid elongated resistor bar centrally disposed within the enclosure and supported at its ends by the said end pieces.

9. A rail heating device comprising a casing extending along the rail and having end pieces secured thereto, said casing forming with the web and base flange of the rail a heat insulated enclosure, an electrical heating element in the form of a resistor bar centrally located in the enclosure and supported at its ends by the end pieces of the casing, and means to electrically insulate the bar from the casing.

10. A rail heating device comprising a protective casing secured to the rail and extending therewith, and a rigid non-metallic electrical resistor bar intermediate the casing and rail and adapted to heat the hollow of the rail solely by radiation.

In testimony whereof, I have hereunto signed my name at Philadelphia, Pennsylvania, this twenty-eighth day of April, 1927.

WILLIAM H. GREENFIELD.
